COMBINED SETS OF COASTERS AND PACKAGE THEREFOR OR SIMILAR ARTICLE

Per E. Wenander, Cincinnati, Ohio,

Application February 25, 1950, Serial No. 8,111

Term of patent 7 years

(Cl. D58—15)

To all whom it may concern:

Be it known that I, Per E. Wenander, a subject of the Kingdom of Sweden, residing at Cincinnati, in the county of Hamilton and State of Ohio, have invented a new, original, and ornamental Design for Combined Sets of Coasters and Package Therefor or Similar Article, of which the following is a specification, reference being had to the accompanying drawings, forming a part hereof.

I claim:

The ornamental design for combined sets of coasters and package therefor or similar article, as shown.

PER E. WENANDER.
